Primary Examiner — Holly E Thurman*Assistant Examiner* — Sharon H Schwartz(74) Attorney, Agent, or Firm — Banner & Witcoff, Ltd.(57) CLAIM

The ornamental design for a shoe as shown and described.

DESCRIPTION

FIG. 1 is a bottom view of a shoe showing our new design; FIG. 2 is a bottom rear perspective view thereof; and, FIG. 3 is an opposite side bottom rear perspective view thereof.

The broken line showing of the racetrack shaped areas represent cutouts that form no part of the claimed design. The broken lines depicting the remainder of the shoe form no part of the claimed design.
